HANGFIRE RECORDER

Herschel Smith and James V. Dunham, Southamton, Pa., and Norman K. Turnbull, Pitman, N. J.

Application August 26, 1941, Serial No. 408,334

22 Claims. (Cl. 234—36.5)

(Granted under the act of March 3, 1883, as amended April 30, 1928; 370 O. G. 757)

1

The invention described herein may be manufactured and used by or for the Government for governmental purposes, without the payment to us of any royalty thereon.

This invention relates to the measurement of the characteristics of ammunition and to apparatus for recording those characteristics.

An object of this invention is to measure the time elapsed between the actuation of the trigger of a projectile firing device and the emergence of the projectile from the muzzle of the device.

Another object of this invention is to have smooth working electronic tube apparatus for producing a permanent record of the hangfire characteristics of ammunition.

Another object of this invention is to measure and record the hangfire characteristics of ammunition by electrostatic means sensitive to the charges produced subsequent to the firing of the ammunition.

Another object of this invention is to incorporate a control circuit in a hangfire measuring circuit so that all of the operating personnel may be behind the firearm when it is discharged thus eliminating possible danger to the health and life of the operating personnel.

Another object of this invention is to perform a hangfire test on blank ammunition.

Another object of this invention is to measure hangfire of ammunition with a limited number of persons.

Another object of this invention is to have hangfire measuring apparatus which may be made portable by one skilled in the art so that hangfire measurements on any caliber weapon in the field might be made.

Another object of this invention is to have hangfire measuring apparatus in which one recorder may be used to record the hangfire characteristics of different caliber ammunition with facility, thus reducing installation costs.

Another object of this invention is to provide a recorder for recording events.

With the foregoing and other objects in view, this invention resides in the novel arrangement and combination of elements necessary for the measurement of hangfire in the manner described, it being understood that changes in the precise embodiment of the invention herein disclosed may be made within the scope of what is claimed without departing from the spirit of the invention.

Practical embodiments of the arrangements utilized are disclosed by way of illustration in the accompanying drawings, wherein:

2

Fig. 1 discloses the disposition of electrical circuit elements and mechanical elements.

Fig. 2 is a plan view of the recorder which is shown schematically in Fig. 1.

Fig. 3 is a side view of the recorder shown in Fig. 2.

Fig. 4 is a view taken substantially on line 4—4 of Fig. 3.

Fig. 5 is a view taken substantially on line 5—5 of Fig. 3.

Fig. 6 is a view taken substantially on line 6—6 of Fig. 2.

Fig. 7 is an elevation, partly in section, of the manual means for rotating the drum shaft.

Fig. 7a is a horizontal sectional view of the means disclosed in Fig. 7.

Fig. 8 is a view taken substantially on line 8—8 of Fig. 3.

Fig. 9 is a view taken substantially on line 9—9 of Fig. 3 and discloses the arrangement of the apertures 132, 132a, etc., in the end of the drum.

The principle of operation of this hangfire recorder resides in the fact that the gases which escape from the muzzle of a gun are electrically charged at a potential different from the muzzle potential. This fact is disclosed in Patent 2,206,927, granted to Norman K. Turnbull and James V. Dunham on July 9, 1940, and also in Patent 2,146,723, granted to James V. Dunham and Ernest R. Rechel on February 14, 1939.

Referring to Fig. 1, the numeral 2 indicates the firearm in which the ammunition to be tested is fired. The gun is grounded electrically as indicated at 2'. A collector 1 is placed near the end of the muzzle of the gun. This collector is charged electrically by the gases which emerge from the muzzle. The collector may be constructed in the manner shown in Fig. 1 of Patent 2,206,927, referred to above. The lead wire 3 is coupled to the grid of the gaseous discharge tube 4, which is referred to in the art as a thyratron tube, through the switch 53 and coupling capacitor 5. The grid of the thyratron tube 4 is biased by the direct current source 6 and associated resistors 7 and 8 so that the tube 4 passes practically no current when normal voltages are applied to the plate of the tube. The resistor 8 is a potentiometer bridging the source 6, both being grounded at their ends distant from the grid, as at 6'.

The capacitor 5 is connected between the grid and cathode of the tube 4 and the principal function of capacitor 5 is to limit high frequency surges so that harmful voltages are not applied to the grid of the thyratron tube 4. The variable potentiometer resistor 8 allows the bias voltage to

be varied at will. The resistors 7 and 8 also serve to dissipate any charges which might accumulate on the collector 1, the capacitor 5, or the capacitor 9 so that spurious action of the tube 4 is prevented.

The cathode of the thyratron tube 4 is connected to ground 13' through the resistor 12 and the primary winding 10 of transformer T. The secondary winding 11 of transformer T is connected to an impulse counting circuit to be described later, through the capacitor 26.

The trigger of the firearm 2 is actuated by a magnetic trigger operating mechanism shown schematically in Fig. 1 and designated as 14. The magnetic trigger operating mechanism may be of any of the well known types and may be of the type described in the copending patent of Norman K. Turnbull and Herschel Smith, No. 2,331,942, October 19, 1943. The ammunition in the firearm 2 is adapted to be fired upon energization of the magnet winding 14. An electronic rectifier 15 of any of the well known types is connected across the magnet winding 14 so that the voltage induced in the winding 14 due to a decaying field in the magnet has little or no effect on the source of power supplying the magnet winding.

The output current of the tube 4 passes through the primary winding 10 of the transformer T through resistor 12 to ground at 13'. The secondary winding 11 is connected across terminals of a spark recorder 18, through ground connections 13' and 18'. The resistor 12 serves to limit the flow of the output current through tube 4.

The mechanical details of the spark recorder are disclosed in Figs. 2-9 and are to be described later. In general, the recorder consists of a rotatable metallic drum 100, grounded at 18', Fig. 1. Means are provided to hold a record sheet about the periphery of the drum. A carriage 160 is mounted for translation adjacent and axially along the drum and a stylus 18", which may be a tungsten wire, is mounted upon this carriage. Circuit connection is made with the stylus such that when a high voltage is induced in the circuit, a spark jumps between the end of the stylus and the drum, and forms a record mark upon the aforesaid sheet. A motor 103 is adapted to rotate the drum and to move the stylus carriage axially therealong, in timed relation. A magnetically operated clutch on the carriage is energizable to connect and disconnect the carriage with the motor. Thus, the carriage is moved only when the clutch is energized.

The power supply for the cathode-plate circuit of the tube 4 is largely supplied from a charged capacitor 22. The capacitor 22 is charged from the A. C. source 19 through the rectifiers 20 and 21. The net effect of the two tubes 20 and 21 is to produce a full wave rectified output. The capacitor 22 is charged through the resistors 23 and 24. The voltage which the capacitor 22 will assume when the relay R₃ is de-energized is determined largely by the value of the resistors 23, 24, and 25. In order to energize the plate of the tube 4, it is necessary that the winding of relay R₂ be energized. The winding of relay R₂ is connected in parallel with the winding of relays R₁ and R₃ so that relays R₁, R₂ and R₃ are always energized simultaneously. The normally open contacts of relay R₂ are connected in parallel to the resistor 23 so that the resistor 23 is short circuited when the relay R₂ is energized. Thus, upon energization of relays R₂ and R₃, the capacitor 22 which has been pre-

viously charged, discharges through the plate-cathode circuit of the tube 4 and since the resistor 23 is short circuited, the D. C. output potential distribution is altered in a direction to tend to make the available power output greater. The current in the output circuit of the tube 4 is in the nature of a pulse and the greater portion of the energy of that pulse is due to the energy which was originally stored in the capacitor 22.

The pulse of current in the output circuit of the tube 4 is partially transformed in the output circuit of the transformer T. The output or secondary winding 11 of transformer T is coupled to the grid-cathode circuit of a thyratron type tube 27 through the capacitor 26 and the indicated ground connections. The resistor 28 and potentiometer 29 tend to limit the flow of grid-cathode current in the tube 27. The source of D. C. potential 30 and adjustable potentiometer 29 produce a variable bias voltage source for the grid of tube 27.

The winding 31, of a counter is connected in the plate circuit of the tube 27. The impulse counter is of the type which registers one impulse each time the magnetizable operating member is displaced in a given direction due to the action of magnet 31. Such impulse counters are well known in the art. Also, the switching element 33 attached to the magnetizable member 32 is adapted to open the pair of contacts 33'. The contacts 33' bridge the parallel circuit formed by the resistor 34 and the capacitor 35. The capacitor 36 is charged from the A. C. source 37 through the rectifying tubes 38, 39 and the inductor 40 in the nature of a choke coil. The resistor 41 stabilizes the output of the rectifier because of the load imposed on the rectifier. The gas discharge tube 27 is biased by the potentiometer 29 so that normally no current flows in the plate circuit. When a pulse is transmitted to the grid of the tube 27, a current flows through the winding 31 and shunt or short path through switch 33 around the parallel circuit 34, 35. Due to the action of the operating member of the device 32, an impulse is registered on the "impulse counter" and simultaneously the parallel elements 34 and 35 are inserted in the plate circuit. Due to the fact that the pulse transmitted to the grid of the tube 27 is of short duration and due to the fact that the current passed at 33 independently of the elements 34 and 35 causes an appreciable drop of potential in the plate voltage of the tube, the tube 27 will return to its normal non-conducting condition after every pulse.

The trigger actuating magnet 14 is energized by the current which flows through the gaseous discharge tube 42. Commutator switches designated as "On" and "Off" control the firing of the tube 42. These switches are separate from one another but are rotated in synchronism with the recording drum. Both switches are closed once per revolution of the recorder shaft and the "Off" switch is closed approximately .010 sec. after the "On" switch closes. The tube 42 is normally biased by the source of D. C. current 43 so that normally no current flows in the output circuit of tube 42. The resistor 44 tends to limit the flow of grid-cathode current. The source of D. C. voltage 45 is connected through the "On" switch and is of sufficient value to cause the tube 42 to become conducting when a pulse is transmitted from this source to the grid of the tube, and while the normal plate potential is

maintained, as will be explained. The resistor 46 tends to limit the flow of current from the source 45.

The plate current of the tube 42 flows through the left part of the resistor 47, the normally open contacts of relay R₄ and of relay R₅, the source of current 52—53 48, the trigger-actuating magnet 14 to the cathode of tube 42. The current will also be augmented by discharge of condenser 48 as elsewhere described. Also, since the capacitor 49 is connected in parallel to the resistor 47, the capacitor 48 will acquire a charge and a potential as indicated in Fig. 1 due to the potential drop across the resistor 47. The capacitor 49 is connected directly across the plate and cathode of tube 42 through the "Off" switch. Since the "Off" switch closes a short time after the "On" switch has closed and opened, the reverse D. C. potential supplied by the capacitor 49 through the "Off" switch is sufficient to extinguish the arc in tube 42. Thus the "On" and "Off" switches effect a recurring current flow in the tube 42 and trigger-actuating magnet 14.

The plate voltage supply for the tube 42 operates in a manner similar to the plate voltage supply for the tube 4. The capacitor 48 supplies most of the energy necessary to actuate the trigger-operating mechanism. The capacitor 48 is charged through the resistor 51 when the tube 42 is not being supplied. The relay R₄ when energized closes the plate supply circuit to the tube 42. The relay R₅ which is operated simultaneously with relay R₄ short circuits the resistor 51 so that a higher voltage may appear across the loading resistor 47. The capacitor 48 is charged through the full wave rectifier comprising the tubes 52, 53 from transformer T₂.

Actuation of the "trigger switch" serves to energize the relays R₁, R₂, R₃, R₄ and R₅ simultaneously, with the result that the plates of tubes 4 and 42 are charged although at the moment neither of the respective tubes is conducting. Also energization of relay R₁ causes the stylus magnets, 170, 171 in Fig. 3, to be energized through a rectifier comprising tube 54, inductor 55 and capacitors 56a and 57a. The resistor 58a is made adjustable and tends to limit the current which flows through the stylus magnets 170, 171. Energization of the stylus magnets 170, 171 allows the tungsten point 18 to move parallel to the axis of the recorder. Thus, the "trigger switch" serves to (1) control the firing of the firearm, (2) control the operation of the recorder input circuit and (3) control the movement of the tungsten electrode 18''.

The function of the "zero shot" switch is to allow the firearm to be discharged once only.

The switches 56, 57, 58 serve to connect the electrical elements associated with the firearm to the hangfire measuring circuit proper. It appears obvious that the switches 56, 57, and 58 may be made in the nature of selector switches so that any one of a plurality of firearms might be connected to the hangfire measuring circuit proper.

The switch 59 serves to connect the A. C. source 60 to motor 103.

Description of recorder structure

The recorder has a drum 100 upon which a piece of recording paper (not shown) may be held by the two axially disposed split resilient bands 101, 102 and it is understood that other types of means may be employed to hold the recording paper on the drum.

The drum 100 is adapted to be driven by the synchronous motor 103 through a clutch 105 (Fig. 6) on the left hand side of the drum in Fig. 2. Gears 108 (on motorshaft 106), 123 (on shaft 125), on shaft 126 and worm 128 are permanently interconnected and are driven by the synchronous motor. Collar 127 is fixed on shaft 125 and has mounted thereon a housing 128 for a spring pressed pin 129 which has a knurled end 130 and its other end 131 adapted to fit in any one of a plurality of equally spaced apertures 132, 132a, etc., forming a concentric series in the end wall of the drum 100 (Fig. 9); the spring 133 acting on shoulder 134 normally biases the head 131 in the direction of the hole 132 and is adapted to fit in any one of the spaced apertures.

The drum driving shaft 125 is free to rotate with respect to the drum 100 when the clutch 105 is in disengaged position; the drum has bearings 135, 136 disposed on each of its ends through which the shaft 125 passes.

Commutator type switches 137, 138 designated as "On" and "Off" switches are rigidly and adjustably mounted on the shaft 125 by set screws 139, 140. The switches are similar in structure and a description of switch 137 will suffice to explain the details of switch 138. Switch 137 (Fig. 5) comprises a rotatable cylinder 141 which is made of insulating material and has a metal commutator contact bar 142 embedded therein; a pair of metallic brush contact members 143 having electrical leads attached thereto are adapted to be engaged by the metallic bar 142 once per revolution of the cylinder 141. The set screws 139, 140 allow the bars corresponding to bar 142 to be set in angular spaced relationship to one another circumferentially of the shaft 125 so as to properly time the associated electrical circuits 144, 145.

The shaft 125 is rotatably supported in bearings 146, 147 (Figure 3) which are formed in the spaced members 148, 149 respectively.

The worm 126 is free to rotate in bearings 150, 151 (Figure 2) in the spaced members 152, 153 respectively and has the gear 124 fixed thereon.

As will be more fully described subsequently, it is necessary before a "zero shot" is made, to index or angularly adjust the drum 100 by hand, 50 with the synchronous motor deenergized. For this purpose there is provided a manual indexing mechanism 104, which is adapted to effect manual rotation of shaft 106 and is operated only when the synchronous motor is deenergized. The synchronous motor shaft 106 is adapted to be held by the inner surfaces of the two halves 109, 110 of a split hollow cylinder (Fig. 7). It is understood that the members 109, 110 may take other forms and shapes as long as they are adapted to be drawn together by the split surrounding clamp 111, the two halves of which are articulated together by pin 112. An adjustable stop 113 mounted on supporting member 114 serves to limit the downward movement of the 60 manual indexing mechanism and to provide an adjustment for its alignment. A manually operable handle 114 is adapted to pass through the slotted portion 115 of the clamp 111 and to be pivoted about the pin 116 which is held by the walls which define the slot. A pin 117 fixedly mounted in the handle is adapted to contact the bottom pair of faces 118 on the lower member of the clamp 111. Counterclockwise rotation of the handle 114 in Figs. 2 and 7 will cause the spaced 75 jaws 119, 120 of clamp 111 to move closer to

gether and thus cause the split halves 109, 110 to frictionally engage the shaft 106; further such rotation will cause the drum 100 to rotate. The split halves 109, 110 have flanges 121, 122 which maintain the split halves in centered relation in the clamp. Gears 108, 123, 124, shaft 125 and worm 126 are permanently interconnected and rotate when the manual indexing mechanism 104 is rotated. A spring 111a having its ends disposed in recesses in the spaced portions 119, 120 serves to hold the manual indexing mechanism 104 in a normally disengaged position.

The supporting members 149, 153, 154, 148, 152 are bolted to the bed plate 155, the latter being the electrical ground involved throughout the system. A housing 156 supported by the supports 149, 153 by bolts 156a, 156b serves to enclose the gears 123, 124, 108.

A carriage 160 is adapted to be moved parallel to the axial direction of the drum 100 due to the rotation of worm 126. The carriage 160 is slideable along the guides 161, 162 which have their ends fixedly mounted to the supports 152, 153. The worm 126 passes slidably through two spaced openings 160a and 160b in the carriage and is engaged by the worm wheel 165 which is normally free to rotate about the cylindrical projection 160c on the carriage; flat head screw 160e holds the worm wheel on the carriage but allows rotation of the worm wheel.

Rotation of the worm wheel may be prevented by magnetic clutch means which are now to be described. The carriage has mounted thereon a pair of magnetic solenoids 170, 171 by means of angle irons 172, 173 and associated screws. Each solenoid has mounted on its upper end a magnetic bar 175 which extends through an aperture 176 in the carriage and abuts a magnetic ring 177 which is concentrically mounted on the worm wheel 165 by means of screws 178. The ring 177 will hereinafter be referred to as the contact ring and each one of the magnetic bars 175 will be referred to as a contact bar. The contact ring 177 normally lightly abuts the contact bars but their contact introduces practically no frictional resistance to rotation of the worm wheel 165. The magnetic attraction between the contact bar and the contact ring, however, is sufficient when the magnetic solenoids 170, 171 are energized, to clutch and hold the worm wheel 165 against rotation whereby the carriage moves on its guides 161, 162. It is understood that one magnetic solenoid may be used instead of the two solenoids disclosed in the drawings in order to accomplish the purposes of this invention. It is preferable that the material surrounding the solenoids be non-magnetic, except the contact ring and contact bar, so that the solenoid is not magnetically short circuited and the full effect of the magnetic field produced is instrumental in stopping the worm wheel promptly when the solenoids are energized to thereby translate carriage 160 axially along rods 161 and 162 in timed relation with rotation of worm 126.

The stylus holder 180 is pivotably mounted on the carriage block 181 by means of the hinge connections 182, 183; one part of each hinge is fastened to the stylus holder 180 and the other part of the same hinge is fastened to the carriage block as shown in Figs. 2 and 8. The carriage block 181 has a groove 184 in each end face which are adapted to receive spring fasteners 185, 186 so that the stylus holder is rigidly held in its operating position. The stylus holder 180 has a centrally disposed hole 187 through which a

metallic wire 18", preferably of tungsten, passes and forms one electrode of the spark recorder. The metallic wire may be frictionally held in the hole 187 or the wire may be held by a set screw 5 in the stylus holder 180. This arrangement provides an adjustable spark gap between the stylus holder and the drum.

Holder 180 is made of dielectric material to insulate stylus 18" from carriage 160. The stylus 10 is connected with the external circuit through lead 192, insulated terminal 188, and a lead, not shown, extending from this terminal to the stylus.

An index member 195 is fastened to the fixed 15 supporting member 148 and has a pointed end positioned adjacent the outside periphery of the collar 127 on the drum shaft 125. The periphery of collar 127 is suitably graduated so that the 20 positions of the shaft 125 and switches 137, 138 may be ascertained. Definite markings are made 25 on the periphery of the collar 127 that correspond to the positions in which the "On" or "Off" switches are in circuit closing position; these markings are very helpful when making "single shot" records since in that case an electrical control circuit is connected through one of the switches which must be closed in order that the "single shot" discharge be produced.

Operation and measurement of hangfire

30 There are essentially three electrical systems involved in the invention and its utilization as disclosed. These comprise, A, a trigger operating system including two alternative operating circuits, one including a rotary circuit-closing switch 137 which determines the rate of sustained rapid fire of the weapon; the other alternate circuit having a manual single shot control; B, a recording system responsive to the discharges of 35 gas incident to firing of the weapon to operate the recorder 100, and C, a counter system operating the counter 32 coincidentally with, but independently of, the recording system and trigger operating system. It is thought the operation 40 of the counter is simple enough and sufficiently apparent to require no extended description.

In the operation of the firing mechanism, when 45 it is desired to fire a single shot, it is unnecessary to have the drum of the recorder device in rotation, but if it is desired to make a record of the shot, the paper sheet is attached as indicated, and the drum rotated and stopped so as to position the stylus in alignment with the proper line on the sheet, the stylus being adjusted longitudinally 50 to the position to begin a line of recordings, or to form one mark in sequence with those of a line already begun. Before any switches are closed, a round of ammunition is chambered in the firearm conventionally and the "zero shot" 55 switch at 50 closed while the trigger switch is left open. The latter will insure that no accidental electrical operation of the firing mechanism can occur until desired. The switches 56, 57 and 58 are closed; the switch 59 in the motor lead open. 60 With the drum in proper position for a recording, the "On" switch 137 will be closed, but the operating plate circuit will be open at relay R4. The biasing potential of the battery 43 will be overbalanced by the potential of battery 45 which 65 maintains the grid at firing potential, so that the tube will conduct whenever the plate circuit is completed at relay R4. The "Off" switch 138 will 70 not be required in this operation.

75 Due to the functioning of the transformer T2, while the relays R4 and R5 are still open the

condenser 48 will become highly charged across the resistor 51, the resistor 47' passing immaterial current.

For this single shot operation, conditions being as stated, as soon as the "trigger" switch is closed, parallel circuits to all of the relays R1, R2, R3, R4 and R5 are closed. The first relay closes a circuit to the stylus magnets of Fig. 1 and Figs. 3 and 8, which is immaterial for this operation, since no rotation of the drum is required (but will be essential in alternative use of the system for rapid fire to operate the switches 137-138). The second relay closes a by-pass or short circuit around the resistance 23 in the system B which will be described subsequently. Relay R3 closes the plate circuit of system C to be later described. Pickup of relays R5 and R4, respectively, short the resistance 51 and complete the plate circuit to the tube 42. At first, the tube grid being now at a high positive potential, the surge from condenser 48 and the rectified current from the transformer combined are effective at the plate and produce a powerful cathode-plate discharge across the tube, operating the trigger device at 14. Then, with a delay proportional to the value of the inductance at R6, and which will approximate 0.01 second, the relay R6 will open the operating grid circuit from the battery 45, and immediately permit blocking of conduction in the plate circuit by the normal biasing voltage of the battery 43. Completion of loading of the coil at R6 will result also in application of the operating voltage of the plate circuit to the cathode in opposition to the negative potential in the lead through the magnet 14. At the same time the condenser 49 discharges through the shorting bypass (around the impedances of R6) completed by the lower contacts and blade of the relay. This develops a negative component at the plate and a further positive accretion at the cathode. The reversal of the polarity of the cathode connection and application of inverted potentials at the plate and cathode by the condenser 49 would in themselves be sufficient to block. The combined effects thus applied to block the tube result in a very abrupt cut-off.

Completion of cutoff of the tube 42 leaves the relay R6 still energized in a circuit completed through resistance 50 from the positive lead of the plate circuit through R6 and the leads from and to the firing device 14, and consequently the tube 42 is maintained in a blocked condition as long as the "trigger" and "zero shot" switches are both closed. The absence of the potentials derived from the condensers 48 and 49, and impedances at 51 and in R6, however, leave the plate circuit ineffective to operate the trigger device at 14, and no further operation of the latter occurs until the zero shot switch or one in the plate circuit is opened and closed again as before mentioned. The firearm mechanism may automatically reload with another round, if it is supplied with belted or magazine ammunition.

Opening of either of the switches mentioned or either of those 57 and 58 will drop the relay R6 and cause a renewal of the operating charge on condenser 48 and raising of the grid at 42 to firing potential.

Closing of either the trigger switch or one of those 57 or 58 while the zero shot switch is closed without changing the remainder of the circuits, will result in a repeated single shot operation of the firing device 14, as before.

In the alternate or rapid fire operation of the system A, the zero shot switch is kept open, and

the relay R6 and its functions are not employed. The motor 103 is kept in operation for driving of the recorder machine parts and for the operation of the "On" and "Off" switches 137 and 138. For system A only these last named two switches are involved, and the recorder operation will be described in relation to system B.

In the firing of typical automatic firearms or machine guns, rates of fire of from say fifty or 10 more for pistols and 100 to 1500 in machine guns are involved, and the frequency of closing of the "On" switch will in the present instance be depended on to determine the rate of fire, instead of depending on the inherent capability of means 15 in the weapon itself for determining the frequency of fire. The invention is principally intended for testing the capability of automatic loading and firing mechanisms to maintain high rates of fire, means being provided to make the 20 firing dependent on the closing of the plate circuit of tube 42.

In rapid fire operation, action at the weapon may be started and stopped by operation of either the trigger switch or one of the switches 57-58 25 while the motor 103 is operating. But it may be stopped at any time by closing the "zero shot" switch with the effect previously described, and consequently also initiated thereafter by opening that switch while the remainder of the switches 30 last named are closed, the "On" and "Off" switches being in continual operation whenever the "trigger" switch is closed.

The organization of the parameters is such 35 that the condensers 42 and 49 can become charged to the desired extent in the interval between shots fired at a maximum rate and the corresponding intervals in interruption of the plate circuit of the tube 42.

In rapid fire operation, switch 59 is closed and 40 the motor 103 is kept constantly in operation. The grid circuit of tube 42 is closed except at the "On" switch, and a tube-blocking, shorting or bypass circuit equivalent to that through the lower contacts of R6 when closed is closed by the "Off" 45 switch alternately with closing of the "On" switch. The commutator of the "Off" switch is adjusted angularly on the shaft 125 in relation to the commutator of the "On" switch so as to close, say, .01 second after closing of the "On" switch.

50 In effect, the operating potential is maintained at the plate for a suitable period before the blocking potential is applied by the "Off" switch, but firing of the tube is caused only by closing of the "On" switch. Consequently, while the trigger switch and switches 57 and 58 are closed and the motor operating there will be a continual intermittent closing of the "On" switch, firing a shot at 14 each time, followed almost immediately by a blocking potential applied to the tube by closing 55 of the "Off" switch, the rate of such fire being dependent on the speed of the motor and the transmission ratio connections in the gear train of Fig. 1.

During operation of the motor, the drum 100 60 is rotated in synchronism with the switch 137, so that a particular line on the attached sheet is aligned with the stylus 18' each time the plate circuit is closed, and the stylus is also moved longitudinally as previously described, so that 65 the stylus is stepped along the line on the paper at each rotation of the drum and firing of the arm 2. Thus, when any recording impulse is transmitted through the stylus for a shot actually manifest at the muzzle of the weapon, a 70 respective discrete record will be formed in an

orderly series on the record sheet. This recording impulse is provided for in system C now to be described.

In system C the tube 4 has its plate supplied as before described in such manner that when the grid potential is raised properly above cutoff a discharge occurs in the cathode-plate circuit for which the rectified current from 20-21 and the charge on the condenser 22 are available. It has been explained in detail how the parameters are organized to establish the plate supply when the relays R2 and R3 are closed, which is a constant condition when the trigger switch is closed to produce the rapid fire operation. Raising of the grid potential to fire the tube is effected by utilizing the charge collected by the ring 1 on each shot, in conjunction with the adjusted critical potential supplied by the source 6 and resistances 7 and 8. When the plate circuit pulse occurs, the pulse thereby induced in the secondary of the transformer 10-11 acts to produce the recording action at the stylus 18" and also to transmit a pulse to the operating tube 27 of the counter system before described in sufficient detail.

It having been before explained how the stylus is positioned on the same line each time the "On" switch is closed, such closure involving a respective shot or failure of the arm, and how the stylus is also stepped horizontally, it is apparent that pulses transmitted to the stylus will produce discrete marks in orderly series, any omissions in which will appear as a blank in a line of marks on the paper record on the drum. The adjustment and functioning of the drum operating and stylus moving means have been before described with sufficient detail so that the utilization of the mechanism will be understood.

It is preferable to control rapid fire operation by means of the trigger switch, because incident to the opening of the latter the relay R1 is opened, which frees the clutch of the recorder, so that the stylus is not moved longitudinally of the drum, and the motor and drum may be kept in operation when no firing is carried on without disturbing the continuity of the record when rapid firing is resumed by closing of the trigger switch. This relay R1 opens and closes a special magnet operating circuit through the rectifier 54 smoothing LC device 55-56 and adjusted resistor 58a before referred to.

The record appears as a row of dots on the waxed paper. The dots are separated by about $\frac{1}{16}$ inch and form approximately a straight line parallel to the axis of the drum. The "zero shot" appears ahead of the main group in line with its beginning. Any blank intervals in a line of dots made during the described rapid fire procedure will represent "hang fires," or the point of stoppage in a sustained burst, the causes of which may be various, and will be independently determined.

In order to make another record on the same piece of paper the drum is rotated with respect to the "On" and "Off" switches by pulling the pin 129 out of the aperture 132 in the drum, Figs. 2 and 6, rotating the drum with respect to the switches and allowing the spring biased pin 129 to fall into an adjacent aperture 132a. Thus another record may be made on the same piece of waxed paper. The two records will be parallel to one another and parallel to the axis of the drum.

When as many records as desired have been made on a sheet of recording paper, it is removed and laid flat on a board against a straight edge. With the help of a triangle the extreme dot posi-

tions are marked (with a line near the edge of the paper) for each group. The "zero shot" position also is similarly marked.

Since the drum rotates at a constant speed for the continuous fire record, the distance between adjacent marks which are due to the spark discharge is a measure of the elapsed time. For practical purposes that distance is measured along a line perpendicular to a line which is parallel to the axis of the drum and is on the paper. Of course, the path of the recording point is a spiral about the drum; but, since the point advances only $\frac{1}{16}$ inch in each 25 inches of peripheral movement of the drum, the error introduced by making the measurements as described is less than $\frac{1}{1000}$ of one percent. The distance (in time units) between the extreme shots of the burst gives the group width. The "zero shot" is measured in the same manner. In our particular apparatus the drum rotates 450 times per minute; its diameter is 7.92 inches. This gives .1866 inch per millisecond for the conversion factor.

We claim:

1. In a system for measuring the characteristics of ammunition propelled from a firearm, electric means for actuating the firing means of the firearm, a recorder having a rotatable drum, a plurality of electric switches, means for actuating said switches in timed relation to the rotation of the recorder, electric means responsive to the presence of the propellant gases from the ammunition for producing indicia on the recorder, and electric means responsive to the actuation of the switches for energizing and deenergizing said first mentioned electric means.
2. In a system for measuring the characteristics of ammunition propelled from a firearm, a magnet coil for actuating the firing means of the firearm, a recorder having a rotatable drum, a plurality of electric switches, means for actuating said switches in timed relation to the rotation of the recorder, electric means responsive to the presence of the propellant gases from the ammunition for producing indicia on the recorder, and electric means responsive to the actuation of the switches for energizing and deenergizing said magnet coil.
3. In a system for measuring the characteristics of ammunition propelled from a firearm, electric means for actuating the firing means of the firearm, a recorder having a rotatable drum, a plurality of electric switches, means for actuating said switches in timed relation to the rotation of the recorder, electric means responsive to the presence of the propellant gases from the ammunition for producing indicia on the recorder, electric means responsive to the actuation of the switches for energizing and deenergizing said first mentioned electric means, and electric means responsive to the actuation of the switches for energizing and deenergizing said indicia producing means.

4. In a system for measuring the characteristics of ammunition propelled from a firearm, a magnet coil for actuating the firing means of the firearm, a recorder having a rotatable drum, a plurality of electric switches, means for actuating said switches in timed relation to the rotation of the recorder, electric means responsive to the presence of the propellant gases from the ammunition for producing indicia on the recorder, electric means responsive to the actuation of the switches for energizing and deenergizing said magnet coil, and electric means responsive to the

actuation of the switches for energizing and de-energizing said indicia producing means.

5. In a system for measuring the characteristics of ammunition propelled from a firearm, electric means for actuating the firing means of the firearm, a recorder having a rotatable drum, a plurality of electric switches, means for actuating said switches in timed relation to the rotation of the recorder, electric means responsive to the presence of propelled gases from the ammunition for producing indicia on the recorder, electric means responsive to the actuation of the switches for energizing and deenergizing said first mentioned electric means recurrently, and electric means coacting with one of said switches constructed, arranged and adapted to assume an inoperative condition with the first named means in response to one energization of the first mentioned electric means.

6. In a system for measuring the characteristics of ammunition propelled from a firearm, a magnet coil for actuating the firing means of the firearm, a recorder having a rotatable drum, a plurality of electric switches, means for actuating said switches in timed relation to the rotation of the recorder, electric means responsive to the presence of propellant gases from the ammunition for producing indicia on the recorder, electric means responsive to the actuation of the switches for energizing and deenergizing said magnet coil recurrently, and electric means coacting with one of said switches constructed, arranged and adapted with and to said coil to assume therewith an inoperative condition responsive to one energization of the magnet coil.

7. In a system for measuring the characteristics of ammunition propelled from a firearm, electric means for actuating the firing means of the firearm, a recorder having a rotatable drum, a plurality of electric switches, means for actuating said switches in timed relation to the rotation of the recorder, electric means responsive to the presence of the propellant gases from the ammunition for producing indicia on the recorder, an electric counter coupled to the last mentioned means for recording the number of said indicia, and electric means responsive to the actuation of the switches for energizing and deenergizing said first mentioned electric means.

8. In a system for measuring the characteristics of ammunition propelled from a firearm, a magnet coil for actuating the firing means of the firearm, a recorder having a rotatable drum, a plurality of electric switches, means for actuating said switches in timed relation to the rotation of the recorder, electric means responsive to the presence of the propellant gases from the ammunition for producing indicia on the recorder, an electric counter coupled to the last mentioned means for recording the number of said indicia, and electric means responsive to the actuation of the switches for energizing and deenergizing said magnet coil.

9. In a system for measuring the characteristics of ammunition propelled from a firearm, electric means for actuating the firing means of the firearm, a rotatable drum adapted to hold recording paper, a magnetic clutch, a stylus for said recording paper movable through the magnetic clutch, a plurality of electric switches, means for actuating said switches in timed relation to the rotation of the drum, electric means responsive to the presence of the propellant gases from the ammunition for producing indicia on the recording paper, electric means responsive

to the actuation of the switches for energizing and deenergizing said first mentioned electric means, and switching means for simultaneously energizing said last mentioned means and the magnetic clutch.

5. 10. In a system for measuring the characteristics of ammunition propelled from a firearm, a magnet coil for actuating the firing means of the firearm, a rotatable drum adapted to hold recording paper, a magnetic clutch, a stylus for said recording paper movable through the magnetic clutch, a plurality of electric switches, means for actuating said switches in timed relation to the rotation of the drum, electric means responsive to the presence of the propellant gases from the ammunition for producing indicia on the recording paper, electric means responsive to the actuation of the switches for energizing and deenergizing said magnet coil, and switching means for simultaneously energizing said last mentioned means and the magnetic clutch.

10. 11. In a system for measuring the characteristics of ammunition propelled from a firearm, electric means for actuating the firing means of the firearm, a recorder, electric means responsive to the presence of the propellant gases from the ammunition for producing indicia on the recorder, and electric means responsive to the indicia producing means for energizing the first mentioned electric means.

11. 12. In a system for measuring the characteristics of ammunition propelled from a firearm, electric means for actuating the firing means of the firearm, a recorder, electric means responsive to the presence of the propellant gases from the ammunition for producing indicia on the recorder, and electric means responsive to the indicia producing means for recurrently energizing the first mentioned electric means.

12. 13. In a system for measuring the characteristics of ammunition propelled from a firearm, electric means for actuating the firing means of the firearm, a recorder, electric means responsive to the presence of propellant gases from the ammunition for producing indicia on the recorder, electric means responsive to the indicia producing means for energizing the first mentioned electric means, and electric means constructed, arranged and adapted to assume with the first-named means an inoperative condition in response to one energization of the first mentioned electric means.

13. 14. In a system for measuring the characteristics of ammunition propelled from a firearm, electric means for actuating the firing means of the firearm, a recorder, a magnetic clutch, electric means responsive to the presence of the propellant gases from the ammunition for producing indicia on the recorder, a stylus for the recorder operable through the magnetic clutch, and switching means for simultaneously energizing said first mentioned means and the magnetic clutch.

14. 15. In recording apparatus, an electric circuit, a rotatable drum adapted to hold paper for recording signals transmitted by the said circuit, a rotatable worm, a carriage, a stylus on the carriage, a worm wheel rotatable on the carriage and adapted to engage the worm, and means responsive to impulses in said circuit for locking the worm wheel against rotation.

15. 16. In recording apparatus, an electric circuit, a rotatable drum adapted to hold paper for recording signals transmitted by the said circuit, a rotatable worm, a carriage, a stylus on the

carriage, a worm wheel having some magnetizable material and rotatable on the carriage and adapted to engage the worm, and magnetic means on the carriage responsive to impulses in said circuit adapted to lock the worm wheel against rotation.

17. In recording apparatus of the character described, a rotatable drumshaft and drum thereon, means to rotate the shaft at constant speed an electrical gun firing circuit including a switch, a fire recording device cooperative with the drum surface constructed to respond to a gun discharge, and including a stylus and means to move the stylus longitudinally of the drum, means responsive to each rotation of the drum to actuate the switch, and means to adjust the angular position of the drum on the shaft.

18. In a gunfire recording device, a rotatable drum, means to rotate the same at constant speed closely approximating in revolutions per minute a maximum rate of fire of a gun measured in rounds per minute, an electrical gunfiring device including a switch and operative connection between the switch and drum to close and open the switch on each revolution of the drum, and a shot recording device cooperatively associated with the drum and responsive to discharge of gases from the muzzle of the gun, including a record forming member movable longitudinally of the drum, and operative connections between the drum and last named member.

19. The structure of claim 18 including means to selectively fix the drum in angular relation to the operative connection between the switch and drum.

20. In recording apparatus, an electric circuit, a rotatable shaft, a drum rotatable thereon, and adapted to support a record sheet thereon, a switch in said circuit, means responsive to each rotation of the shaft for actuating the switch, record forming means connected in said circuit constructed and arranged to form on said sheet a record of pulses transmitted in said circuit said record-forming means including a point member movable longitudinally beside the drum operative to form respective discrete records on said sheet in response to said pulses, means operatively connected to the shaft to progressively move the point member longitudinally of the drum, means operatively connected with the drum to enable the adjustment of the recording operation of said record-forming means in relation to the angular position of the shaft, means to rotate the shaft and means coupling the drum for releasing the shaft in selective angular relation thereto.

5 21. In a recording apparatus of the character described, a rotating drum shaft, a relatively rotatable record drum thereon, a parallel rotatable worm shaft geared to the drum shaft, a carriage 10 slideable along the worm shaft, electrical means to connect the worm shaft in driving relation to the carriage and including a switch; means to fix the drum on the drum shaft in selective angular relation thereto, a recording device on the carriage, means for operating the drum shaft, a main control circuit operatively associated with said switch and means responsive to operation of the shaft to open and close the circuit.

15 22. The structure of claim 21 in which the means to connect the worm shaft and carriage comprises a worm gear engaged with the worm shaft mounted revolubly on the carriage in a plane coincident with the axis of the shaft, a magnetic brake device operatively associated with the gear and a control therefor including said switch.
